(57) **CLAIM**

I claim the ornamental design for a generally elliptical scalloped food service dish, as shown and described.

DESCRIPTION

FIG. 1 is a top perspective of a generally elliptical scalloped deep food service dish showing my new design;

FIG. 2 is a front elevation thereof;

FIG. 3 is a side elevation thereof;

FIG. 4 is a top plan view thereof;

FIG. 5 is a bottom plan view thereof;

FIG. 6 is a bottom perspective view thereof; and,

FIG. 7 is a bottom perspective of a modified embodiment of the design shown in FIGS. 1 through 6.
